[57] CLAIM

The ornamental design for an inflatable cushion, as shown and described.

DESCRIPTION

FIG. 1 is a perspective view of an inflatable cushion showing my new design;

FIG. 2 is a top plan view thereof, the bottom being a mirror image of that shown; and

FIG. 3 is a side elevational view thereof, the opposite and adjacent sides being substantially similar in appearance.

*Fig. 1**Fig. 2**Fig. 3*
